UNITED STATES PATENT OFFICE.

MICHAEL M. MCINTYRE, OF CLEVELAND, OHIO, ASSIGNOR, BY MESNE ASSIGNMENTS, TO THE STANDARD PARTS COMPANY, OF CLEVELAND, OHIO, A CORPORATION OF OHIO.

PLATE-BENDING MACHINE.

1,295,542.

Specification of Letters Patent. Patented Feb. 25, 1919.

Application filed August 4, 1913. Serial No. 782,821.

To all whom it may concern:

Be it known that I, MICHAEL M. MCINTYRE, a citizen of the United States, residing at Cleveland, in the county of Cuyahoga and State of Ohio, have invented a certain new and useful Improvement in Plate-Bending Machines, of which the following is a full, clear, and exact description, reference being had to the accompanying drawings.

This invention relates to spring-making machines and more particularly to machines employed for bending or cambering spring leaves. It is the general object of the invention to provide a machine of this kind which, while extremely simple in construction, may be easily and conveniently adjusted to accommodate and produce various curvatures in the spring leaves. A further object of the invention is to produce a machine of this type which is convenient and simple of operation. Further and more limited objects of the invention will appear hereinafter. Generally speaking, my invention may be defined as consisting of the combinations of elements set forth in the claims hereto annexed and illustrated in the drawings forming part hereof, wherein: Figure 1 represents a front elevation and Fig. 2 a central sectional view taken through a machine constructed in accordance with my invention showing the parts in the position which they occupy when separated for the purpose of inserting or removing the leaves; and Figs. 3 and 4 are views, similar to Figs. 1 and 2, respectively, showing the parts in closed or "cambering" position.

Describing by reference characters the various parts illustrated herein, 1 denotes a pair of longitudinal sills and 2 one of the cross sills of a frame supporting the mechanism. At the end of the frame opposite the cross sill 2 there is provided a combined cross sill and bed plate 3, the last mentioned sill being conveniently cast with the sills 1, to form a rigid construction. In addition to the longitudinal side sills 1, a sufficient number of intermediate sills will be provided, three such intermediate sills being illustrated, the central sill being indicated at 4 and the sills on each side of the central sill being indicated at 4^a.

For convenience of description, it will be assumed that the frame is supported in a vertical position and that the bed plate 3 is

at the lower end of the frame. This bed plate is generally convex in outline, the convex upper surface being formed by a series of stepped surfaces 3^a. The bed plate is preferably a casting comprising a web having a wide rib surrounding the same, and the upper portion of this rib is provided with the steps referred to.

A series of templet-sections 5 are provided with stems 6 which extend through the stepped rib, set screws 7 being provided for holding these sections in any adjusted position. These templet sections constitute plate-engaging members, are preferably rounded on top, as shown, and are of such width as to be in substantial contact with each other from side to side of the frame.

Slidably mounted on the frame, above the templet bed plate 3 is a cross head 8. This cross head is provided in its lower surface with a rib 9 which is curved and stepped complementarily to the stepped rib on the bed plate and in which rib there are adjustably mounted templet sections 10, set screws 11 being provided to hold these in any convenient adjusted position.

The upper end of the cross head 8 is provided with a shaft 12 journaled in bearings 13 and to which there is connected a pair of links 14, said links being secured to the shaft by means of set screws 15. The upper ends of the links 14 are connected by a cross bar 16, which extends through a lever 17 pivoted to a pair of lugs 18 rigid with the end of the central sill 4 which is extended beyond the cross-sill 2 to provide a support for said lever. The lever 17 extends beyond its point of connection with the links 14 and is there provided with an operating handle 19.

With the construction as shown and described, it is believed that the operation will be clear. The templet sections 5 and 10 are adjusted to the curvature which is desired for any particular run of plates. The lever handle is moved upwardly, as shown in Figs. 1 and 2, moving the cross head 8 away from the bed plate and providing a space between the upper and lower templet sections whereinto the spring plate may be inserted. On moving the lever handle downwardly, the links 14 and 17 operate as a toggle joint, forcing the cross head 8 toward the bed plate and bending and clamping the spring plate in the manner shown in Figs. 3 and 110.

4. The parts are so arranged that, when the spring-plate between the cambering forms or heads is thus clamped, the links 14 and the part of the lever 17 which extends from the shaft 16 to the lugs 18, will form a straight line, thereby locking the cambering forms against the plate. When the leaf is "set" the lever is moved in the reverse direction and the leaf removed and 10 "quenched" in the ordinary manner.

While, for convenience of description, it has been assumed that the frame work 1 will be in a vertical position, this assumption is merely for convenience of description, as 15 the frame work may be arranged in a horizontal plane without affecting the operation.

By the construction described and illustrated herein, it will be apparent that I have produced a machine which is particularly simple of construction and which is 20 capable of a convenient and wide range of adjustment.

Having thus described my invention, what I claim is:—

25. 1. In a machine of the character set forth, the combination of a pair of cambering heads, and means for moving one of said heads toward and from the other, the said means comprising a lever pivoted at one end 30 and at one side of one of said heads and a toggle link connected to said lever and to the last-mentioned head, the parts being so arranged that the toggle link and the portion of the lever extending therefrom to the pivot 35 or fulcrum will form a straight line when the heads are in engagement with an interposed plate thereby to lock the heads in clamping position.

2. In a machine of the character described, 40 the combination, with a fixed cambering head and a cambering head movable toward and from the first mentioned head, of a pair of toggle links rotatably connected each at one end to the movable head, a 45 lever pivoted at one end at one side of the movable head and beyond the adjacent ends of said links, and means pivotally connecting such last mentioned ends of said links to said head, the parts being so arranged 50 that the part of the lever extending from the point of connection with the links to the fulcrum or pivot provides with the said links

a toggle, the links whereof are in the same straight line when the two heads are in operative relation to the interposed plate 55 thereby to lock the plate during the cambering operation.

3. In a machine of the character described, the combination, with a form having a cambering head rigid therewith and provided with longitudinal sills extending from said head and with a central intermediate sill extending beyond the first mentioned sills, of a cambering head slidably mounted upon the first two sills, a link pivotally connected to the last mentioned head, and a lever connected at one end to the intermediate sill and at an intermediate portion to said link, the parts being so arranged that, when the movable head is in engagement with a plate interposed between the same and the fixed head, said link and the portion of the lever extending between said link and the pivot or fulcrum will form a straight line thereby to lock the 75 heads in cambering position.

4. In a machine of the character described, the combination, with a form comprising a fixed cambering head, a pair of longitudinal sills extending therefrom, 80 cross-sills connecting the ends of the longitudinal sills which are opposite said head and a central intermediate sill extending from said head beyond said cross-sill, of a movable cambering head slidably mounted 85 upon the longitudinal sills, a lever pivoted at one end to the portion of the central sill which extends beyond the cross-sill, and a link pivotally connected to the movable head and to said lever intermediate of the ends 90 thereof, the parts being so proportioned that the said link and the portion of the lever extending therefrom to the fulcrum or pivot will be in a straight line when the movable head is in operative relation to a plate interposed 95 between the same and the fixed head, thereby to lock the said heads in cambering position.

In testimony whereof, I hereunto affix my signature in the presence of two witnesses. 100

MICHAEL M. MCINTYRE.
